UNITED STATES PATENT OFFICE.

ANDREW VRUDNY, OF ARNOLD, PENNSYLVANIA.

RAIL-JOINT.

1,300,060.

Specification of Letters Patent.

Patented Apr. 8, 1919.

Application filed January 10, 1919. Serial No. 270,485.

To all whom it may concern:

Be it known that I, ANDREW VRUDNY, a citizen of the Republic of Czecho-Slovak, and resident of Arnold, in the county of 5 Westmoreland and State of Pennsylvania, have invented a new and useful Improvement in Rail-Joints; and I do hereby declare the following to be a full, clear, and exact description thereof.

10 My invention relates to rail joints and has special reference to metallic joints for use in connecting up the ends of two railroad rails.

15 The object of my invention is to form a cheap, simple and efficient rail joint, which can be applied to and be connected between the ordinary railroad rails, and which will do away with the usual bolts and nuts so commonly used in this class of joints.

20 To these ends my invention consists, generally stated, in the novel arrangement, construction and combination of parts, as hereinafter more specifically set forth and described and particularly pointed out in the 25 claims.

To enable others skilled in the art to which my invention appertains to construct and use my improved joint, I will describe the same more fully referring to the accompanying drawing, in which:

Figure 1 shows a side elevation showing the end portions of two railroad rails with my improved joint applied to and between the same;

Fig. 2 is a longitudinal section of the same on the line 2-2 Fig. 1 and looking in the direction of the arrows;

Fig. 3 is a cross-section of the joint on the line 3-3 Fig. 1;

Fig. 4 is a perspective view of one of the splice or joint bars employed; and

Fig. 5 is a view showing another form of my invention.

Like symbols of reference herein indicate like parts in each of the figures of the drawing.

As illustrated in the drawings 1 represents the end portions of two ordinary railroad T rails, which are provided with the usual heads 2, webs 3 and base or flanges 4. Placed on each side of the rails 1 are the splice or joint bars 5, which fit against such rail sides and are provided with the upward extending body portions 6 for fitting against the webs 3 of such rails and with the out-

wardly extending flange portions 7 projecting out from such body portions for fitting over the flanges 4 of such rails. In the center of each of the joint bars 5 is an enlarged portion 8 which is provided with the extension or top portion 9, side portion 10 and bottom portion 11. The top portion 9 is provided with a tapered face 12 at its outer side edge, and the side portion 10 is provided with the angular sided wedge seat 13 within 60 the same and which has its two side faces 14 tapered inwardly from the top of top portion 9 to the bottom of the extension or bottom portion 11. Fitting within the wedge seats 13 in the bars 5 is the wedge block 15, 70 which is provided with the angular sided wedge faces 16 for engaging in and interlocking with the faces 14 in the enlarged portion 8, and which faces 16 are tapered in the same direction as the faces 14. Above 75 the wedge faces 16 on the wedge 15 is the head 17 which conforms in shape to the heads 2 of the rails 1, and such head is provided with a seat 18 having the tapered lips 18' extending down from the same for engaging with the tapered faces 12 thereon, and respectively on the enlarged portion 8. A wedge pin 19 passes through tapered apertures 20 and 21 in the body portions 9 of the bars 5 and wedge 15, respectively, to 80 assist in holding the wedge 15 in place in said bars.

My improved joint is assembled by placing the side bars 5 on each side of the rails, so that the enlarged portions 8 on said bars 90 will come between the ends of said rails, and after this is done, the wedge 15 is forced down in the wedge seat 13 in said enlarged portions in any suitable manner. This placing of the wedge 15 in the seat 13 will act 95 to force inward the bars, so that such bars will bind against the rail webs 3 and rail flanges 4 by the body portions 6 and flanges 7 respectively on said bars, and this inward motion will be further assisted by the tapered lips 18' on the head 17 of said wedge 15 wedging down on the tapered face 12 of the top portions 9.

When my improved joint is thus assembled in place, the ends of the webs 3 and flanges 4 on the rail 1 will abut against the side portions 10 and bottom portions 11 respectively, on the enlarged portions 8 of the joint bars 5, and the ends of the heads 2 of such rails will abut against the ends of the 110

head 17 on the wedge 15, when such bars and such wedge are in position.

If desired, such as in case of the joint on switches, each of the bars 5 can be provided with a pin 22 at one end of the same for fitting within a slot 23 in the rail web 3, in order to assist in holding the rails and joint in place against any side thrusts, and if desired a liner 24 of wood or other suitable material can be placed between the web 3 and the body portion 6 of the bars 5 to act as a filler between the parts to assist in tightening the same.

As shown in Fig. 5, the top portion 9 can be dispensed with and the outer sides of the joint bars 5 rounded, as at 25, for fitting against similar shaped faces on the block 15.

Various other modifications and changes in the design and construction of my improved joint may be resorted to, without departing from the spirit of the invention, or sacrificing any of its advantages.

It will thus be seen that my improved joint can be easily and cheaply manufactured, can be quickly and conveniently assembled in place, and when in position will hold the rails firmly and securely together and in place, while it will also be obvious that when in place the head on the wedge block 30 will close the joint or opening between the rails and form a continuous rail with the parts interlocked.

What I claim as my invention and desire to secure by Letters Patent is:

35 1. In a rail joint the combination with the two rails, of a joint bar on each side of said rails, said bars each being provided with an enlarged portion fitting between the rails and having angular faces to form a wedge seat between the same, a wedge block having angular faces fitting in said seat, and a head on said block for fitting between and conforming to the heads on the rails.

45 2. In a rail joint, the combination with the two rails, of a joint bar on each side of said rails, said bars each being provided with an enlarged portion fitting between the rails and having angular faces to form a wedge seat between the same, a wedge block having angular faces fitting in said seat and a head on said block for fitting between and conforming to the heads on the rails, said faces on said enlarged portions and said block being tapered inwardly.

55 3. In a rail joint, the combination with the two rails, of a joint bar on each side of said rails, said joint bars each being provided with an enlarged portion fitting between the rails and having angular faces to form a

wedge seat between the same, a wedge block 60 having angular faces fitting in said seat, a head on said block for fitting between and conforming to the heads on the rails, and extensions on the top of said enlarged portions adapted to fit within a seat in the bottom of said head.

4. In a rail joint, the combination with the two rails, of a joint bar on each side of said rails, said joint bars each being provided with an enlarged portion fitting between the rails and having angular faces to form a wedge seat between the same, a wedge block having angular faces fitting in said seat, a head on said block for fitting between and conforming to the heads on the rails, extensions on the top of said enlarged portions adapted to fit within a seat in the bottom of said head, and tapered sides on said extensions for engaging with tapered lips on said head.

5. In a rail joint the combination with the two rails, of a joint bar on each side of said rails, said bars each being provided with an enlarged portion fitting between the rails and having angular faces to form a wedge seat between the same, a wedge block having angular faces fitting in said seat, a head on said block for fitting between and conforming to the heads on the rails, and a wedge pin passing through said bars and said block.

6. In a rail joint the combination with the two rails, of a joint bar on each side of said rails, said bars each being provided with an enlarged portion fitting between the rails and having angular faces to form a wedge seat between the same, a wedge block having angular faces fitting in said seat, a head on said block for fitting between and conforming to the heads on the rails, and pins on said bars for fitting within holes in the webs of said rails.

7. In a rail joint the combination with the two rails, of a joint bar on each side of said rails, said bars each being provided with an enlarged portion fitting between the rails and having angular faces to form a wedge seat between the same, a wedge block having angular faces fitting in said seat, a head on said block for fitting between and conforming to the heads on the rails, and a filler between said rails and said bars.

In testimony whereof, I the said ANDREW VRUDNY have hereunto set my hand.

ANDREW VRUDNY.
